UNITED STATES PATENT OFFICE.

ALOIS HELFENSTEIN, OF VIENNA, AUSTRIA-HUNGARY.

APPARATUS FOR REFINING METALS BY HEATING.

1,220,111.

Specification of Letters Patent. Patented Mar. 20, 1917.

Application filed June 5, 1912. Serial No. 701,881.

To all whom it may concern:

Be it known that I, ALOIS HELFENSTEIN, citizen of the Republic of Switzerland, and a resident of Vienna, Austria-Hungary, have invented new and useful Improvements in Apparatus for Refining Metals by Heating, of which the following is a specification.

In refining metals heating first by means of fuel and subsequently by electricity 10 through the medium of electric arcs or slag resistance heating is known. According to that process the current conveying electrodes must be inserted each time in the furnace for use and be removed therefrom during the 15 fuel heating period. In consequence of the wearing away of the electrodes, electric and fuel heating cannot be employed at the same time.

Further the introduction to the bath of 20 electric short-circuit heating by second class conductors after the ordinary process is carried out for the purpose of obtaining high class steel in a Bessemer converter or Martin furnace is also known. The electric current in this case is carried transversely through the bath which in consequence of its great depth requires very great current strength for its heating.

The present invention is carried out in the 30 following manner: In a long tubular furnace a metal bath layer which is very thin relatively to the diameter is heated by the direct passage of current in the longitudinal direction of the metal bath as well as by 35 fuel heating over the bath for the purpose of effecting the refining process more quickly and more satisfactorily. The thin extended metal bath presents on the one hand to the fuel heating and to the refining substances 40 a surface which is large relatively to the cross section of the bath so that the refining action is more quickly effected. On the other hand the heating of shallow baths requires less strength of current and the extended form of the bath enables higher potential to be employed, so that the electric heating is more intense, and the process accelerated. Moreover the gas removal period (deoxidation) in connection therewith cooling 45 must be again effected, can be more quickly carried through.

As compared with the known process referred to, it is possible with the present invention, in consequence of the extended form 55 of the furnace and the arrangement of the current producing pole at the ends of the

furnace, to effect by powerful cooling action without particular disadvantage, complete freezing on each side of the bath to the extent of 1 meter, whereby it is possible to 60 employ poles consisting of first class conductive material, and to avoid powerful intermediate resistances. Such a measure would make the process practically impossible with the furnace employed for known 65 processes.

In consequence of the ample heating of the metal bath by the electric current it is not necessary that the fuel heating should attain the high temperature over the bath 70 as with ordinary reducing furnaces, which is a considerable advantage as regards the admissibility of fuel and the slighter strain on the apparatus.

Now in order to effect a thorough mixing 75 of the metal and eventually of the additional substances, during the process the furnace either effects a rotary or swinging movement around the longitudinal axis or a tilting movement in the direction of the 80 ends.

The two movements may also be employed in combination.

Figures 1 and 2 of the drawing are respectively a vertical longitudinal section and 85 a transverse section of a furnace for carrying out the process.

The suitably tubular formed, Martin furnace 1 is charged through the openings 2 with fluid or cold charge and additional substances and receives the heating gas for carrying out the normal Martin process through the generator 3. In the bottom of the furnace the tube has inserted poles 4 through which the short circuit current from 90 the dynamo engine or from a division of a transformer secondary current circuit can be transmitted at any time to the bath. 95

The poles consist of first class conductors, are water cooled and inserted so that they 100 come into direct contact with the metal bath, and are connected outside the furnace with the source of current, but notwithstanding their arrangement are situated outside the fuel heating zone, and are thus not exposed 105 to the high temperature.

The tubular furnace is suitably seated on rollers 6 and can be swung and rotated around its axis by a suitable driving mechanism. The movement can be effected intermittently, so that the intermissions are always concurrent with the carrying out of 110

the process. As shown in Fig. 1 and indicated in Fig. 2, the furnace in its center is provided with roller races 7 for the reception of the rollers 6 and separated by a channel 8 within which a worm gear 9 is provided meshing with a worm 9' on a shaft 10 provided with a hand wheel 11 for rotating said shaft and by means of the worm gear also the furnace around its longitudinal axis.

Having now particularly described and ascertained the nature of my said invention, and in what manner the same is to be performed, I declare that what I claim is:

An apparatus for refining metals by heating comprising in combination, a long tubular furnace provided with charging openings

and adapted to receive a thin metal bath, means for heating said bath by fuel, water cooled conductors extending with their ends into said bath within said furnace through the bottom thereof for short circuiting said bath, means for imparting to said furnace an intermittent rotary movement around its longitudinal axis, and means for supplying energy to said conductors, substantially as described.

In testimony whereof I affix my signature in presence of two witnesses.

ALOIS HELFENSTEIN.

Witnesses:

AUGUST FUGGER,
IGNAZ KUON SCHNACHY.
